(57) **CLAIM**

The ornamental design for a folding ladder, as shown and described.

DESCRIPTION

FIG. 1 is a left side elevation view of a handrail ladder showing the new design in a first state;
 FIG. 2 is a right side elevation view thereof;
 FIG. 3 is a front elevation view thereof;
 FIG. 4 is a rear elevation view thereof;
 FIG. 5 is a top plan view thereof;
 FIG. 6 is a bottom plan view thereof;
 FIG. 7 is a first perspective view thereof;
 FIG. 8 is a second perspective view thereof;
 FIG. 9 is a front elevation view of a folding ladder shown in a second state;
 FIG. 10 is a rear elevation view thereof;
 FIG. 11 is a left side elevation view thereof;
 FIG. 12 is a right side elevation view thereof;
 FIG. 13 is a top plan view thereof;
 FIG. 14 is a bottom plan view thereof;
 FIG. 15 is a first perspective view thereof; and,
 FIG. 16 is a second perspective view thereof.
